Application July 31, 1953, Serial No. 371,563

1 Claim. (Cl. 20—4)

This invention relates to wardrobe structures, and more particularly to a combination partition and wardrobe adapted to be used as a transverse partition between a pair of opposing walls.

A main object of the invention is to provide a novel and improved combination wardrobe and partition, the improved structure involving simple components, being easy to install, and providing maximum utilization of space in a room, as well as providing a plurality of wardrobes which are convenient of access and compact in size.

A further object of the invention is to provide an improved wardrobe unit of inexpensive construction which may be employed as a partition between a pair of opposing walls, the wardrobe unit being neat in appearance, being durable in construction, and employing prefabricated components, whereby it may be installed with a minimum expenditure of time and labor.

Further objects and advantages of the invention will become apparent from the following description and claim, and from the accompanying drawings, wherein:

Figure 1 is an elevational view, partly broken away, of an improved wardrobe unit constructed in accordance with the present invention, shown installed between a pair of opposing walls, in a room.

Figure 2 is a top plan view of the wardrobe unit shown in Figure 1.

Figure 3 is a vertical cross sectional view taken on the line 3—3 of Figure 1.

Figure 4 is a horizontal cross sectional view taken on the line 4—4 of Figure 1.

Figure 5 is a vertical cross sectional view taken on the line 5—5 of Figure 3.

Figure 6 is an enlarged cross sectional detail view taken on the line 6—6 of Figure 1.

Figure 7 is an enlarged vertical cross sectional detail view taken on the line 7—7 of Figure 1.

Figure 8 is a fragmentary vertical transverse cross sectional detail view taken through the top portion of a modified form of combination wardrobe and partition constructed in accordance with the present invention.

Referring to the drawings, and more particularly to the form of the invention illustrated in Figures 1 to 7, 11 and 12 designate a pair of opposing walls in a room between which it is desired to install a partition. In accordance with the present invention, a combination partition and wardrobe unit, designated generally at 13 is installed between the opposing walls 11 and 12.

The wardrobe structure 13 comprises a pair of vertical, spaced, stationary panels 14 and 15 secured in a common transverse plane in abutment with the respective opposing walls 12 and 11 and a third stationary vertical panel 16 secured in a transverse plane offset from the first-named vertical plane and located intermediate the opposing walls 11 and 12. Designated at 17 and 18 are respective vertical side panels connecting the inner side marginal portions of the panels 14 and 15 with the respective side marginal portions of the intermediate vertical panel 16. Thus there is defined a first closet space

- 19 between the side panels 17 and 18 and a pair of additional closet spaces 20 and 21 defined respectively between side panels 17 and wall 12 and between side panel 18 and wall 11. As is clearly shown in Figure 4, the closet spaces 20 and 21 open on one side of the unit and the closet space 19 opens on the opposite side of the unit, thereby providing two closets in the room space on one side of the unit and a third closet in the room space on the other side of the unit.
- 10 Designated at 22 is a rectangular top wall which is secured on the top edges of the vertical panels 14, 15, 16, 17 and 18 and which extends for the entire distance between the opposing walls 11 and 12. At its opposite longitudinal edges the horizontal top wall 22 is provided with the respective depending flange elements 23 and 24 which are coextensive in length with the top wall 22. Secured to said flange elements beneath the side marginal portions of the top wall 22 are the respective inwardly facing generally C-shaped roller tracks 25 and 26. Movable supported on the roller track 25, as by suitable rollers 27 journaled on horizontally extending shaft elements 28 secured to its top marginal portion is a sliding door 29 which is thus supported by the top wall 22 for movement parallel to the stationary vertical panels 14 and 15 in a plane outwardly adjacent to the common transverse plane in which the panels 14 and 15 are located. As will be readily apparent from Figure 4, the sliding door 29 is movable across the front of the closet space 19 and thus defines a sliding closure therefor.
- 30 The lower portion of the sliding door 29 is slidably engaged with the floor adjacent the front of the closet space 19 by the provision of a groove 31 in the bottom edge of the door which receives an upstanding pin 31 provided in the floor under the bottom edge of the sliding door 29. Obviously, any other well known form of sliding connection between the bottom of the sliding door 29 and the floor subadjacent thereto may be provided, the details of said sliding connection forming no part of the present invention.
- 40 Slidably supported on the guide track 26 in the same manner as door 29 are the additional sliding doors 32 and 33, said sliding doors being supported from the left side marginal portion of the top wall 22, as viewed in Figure 3, for sliding movement in a transverse vertical plane parallel to the plane of the vertical panel 16 and located outwardly adjacent to the plane of said panel 16. The lower portions of the sliding doors 32 and 33 are slidably connected to the floor by the use of guide pins similar to those employed for the sliding door 29 so that the sliding doors 32 and 33 are guided for sliding movement across the fronts of the respective closet spaces 20 and 21 and thereby define sliding closures therefor. As will be apparent from Figure 4, either of the sliding doors 32 and 33 may be opened when the other sliding door is in closed position, whereby the closet space to be opened may be exposed by moving its sliding door adjacent to the vertical panel 16.
- 50 Since the sliding doors 32 and 33 are disposed in a common vertical plane (Figure 4), and since their movement in directions outwardly from the intermediate or first closet space into positions closing their associate closet spaces 20 and 21 is limited by the opposing walls 11, 12, and since, further, their movement in opposite directions is in the mentioned common vertical plane, it will be seen that when the doors 32, 33 are moved to positions opening their spaces 20, 21, any one of them that is so moved will abut against the other. Thus, if sliding door 32 is moved to an open position from its Figure 4 position, it will be limited in such movement by abutting against the sliding door 33. In these circumstances, the door 32 will be disposed in back of the first closet space 19. It thus becomes apparent that each
- 60
- 65
- 70

of the additional sliding doors 32, 33 is mounted for and is limited to movement between opposite extreme positions, in one of which it extends as a closure for its associated additional closet space, and in the other of which it extends across the back of the first closet space 19 into abutting relation to the other additional sliding door.

Designated at 34 is an upstanding rectangular vertical panel which is secured longitudinally to the intermediate portion of the top wall 22 and which is coextensive in length with said top wall, whereby the upstanding panel 34 extends between the opposing walls 12 and 11 and provides a vertical extension of the partition defined by the wardrobe unit. In the form of the invention illustrated in Figures 1 to 7, a single upstanding partition 34 is employed, which projects upwardly for any desired distance, and which may extend completely to the ceiling of the room.

In the form of the invention illustrated in Figure 8, a pair of upstanding rectangular vertical panels 35 and 36 are secured to the respective longitudinal marginal portions of the top wall 22, the panels 35 and 36 being coextensive in length with said top wall, whereby they extend between the opposing walls 11 and 12 and provide a flush extension of the wardrobe unit on the opposite sides thereof which extends completely to the ceiling 37 of the room.

As shown in Figures 1, 3 and 5, suitable shelves 38 may be provided in the upper portions of the closet spaces 19, 20 and 21, and a hanger rod 39 may be secured between the opposing walls 11 and 12 subadjacent the shelves 38.

While certain specific embodiments of an improved combination wardrobe unit and partition have been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A wardrobe unit adapted to be used as a transverse par-

tition between a pair of opposing walls comprising a pair of spaced stationary vertical panels secured in a common transverse plane in abutment with the respective opposing walls, a third stationary vertical panel secured in a transverse plane offset from the first-named vertical plane and located intermediate said opposing walls, respective vertical side panels connecting the inner side marginal portions of the first-named vertical panels to the respective side marginal portions of the last-named vertical panel, defining a first closet space between said side panels and a pair of additional closet spaces between the side panels and the respective opposing walls, a rectangular top wall secured on the top edges of said vertical panels and extending between said opposing walls, said top wall having its respective longitudinal marginal portions projecting outwardly beyond the respective transverse planes, a first sliding door slidably supported by one longitudinal marginal portion of said top wall for movement parallel to said first-named vertical panels across the front of said first closet space and defining a sliding closure therefor, and a pair of additional sliding doors respectively slidably supported by the opposite longitudinal marginal portion of said top wall for movement parallel to said third vertical panel across the front of the respective additional closet spaces and defining sliding closures therefor, each of said additional sliding doors being mounted for and being limited to movement between opposite extreme positions in one of which it extends as a closure for its associated additional closet space and in the other of which it extends across the back of the first closet space into abutting relation to the other additional sliding door.
